ALONZO LINTON BAUSMAN, OF CHICOPEE, AND DANIEL C. COTTREAL, OF SPRINGFIELD, MASSACHUSETTS, ASSIGNORS TO THE NATIONAL EQUIPMENT COMPANY, OF SPRINGFIELD, MASSACHUSETTS, A CORPORATION OF MASSACHUSETTS.

PACKING-TABLE.

1,023,103.

Specification of Letters Patent.

Patented Apr. 9, 1912.

Application filed October 31, 1911. Serial No. 657,848.

To all whom it may concern:

Be it known that we, ALONZO LINTON BAUSMAN and DANIEL C. COTTREAL, both citizens of the United States of America, residing at Chicopee and Springfield, respectively, in the county of Hampden and State of Massachusetts, have jointly invented new and useful Improvements in Packing-Tables, of which the following is a specification.

This invention relates to a packing table of a kind particularly useful to aid in packing candy.

The structure embodied in this invention may be used for many purposes besides the particular one referred to.

In packing assorted candies and the like, the common method is for each packer to pick out the different kinds of candy in regular rotation from a suitable receptacle which contains the candies in certain definite proportions. It is desirable for the manufacturer to have his product uniform, and heretofore there has been much trouble because the packers can not be depended upon to pick out the different kinds of candy in the proper way. Some kinds of candy intended for the mixture in each box would be slighted and after the packers have been working several hours at the usual method of packing, it has been found that the product in each box is not the kind of a mixture desired. The result is clearly undesirable, not only as to the product but also because the manufacturer can not definitely determine just how much candy of each grade he can safely make up to yield a given number of boxes with the proper proportion of each grade in the mixture.

It is the object of this invention to avoid the difficulties referred to in packing assorted candies.

Another object of the invention is to provide a structure which will require the packers to work at a uniform speed and which will afford a means of checking up the work of the packers. If any packer neglects to keep up to the required rate of work, this fact will immediately be apparent.

Other objects of the invention will appear in the detailed description of the invention and in the claims.

In the drawings forming part of this application,—Figure 1 is a top plan view of

the apparatus. Fig. 2 is a side, sectional view taken on the line 2—2 of Fig. 1 looking in the direction of the arrow. Fig. 3 is a sectional view taken on the line 3—3 of Fig. 1. Fig. 4 is an end view of the apparatus assembled. Fig. 5 is an enlarged view of the mechanism directly involved for transferring the trays on the outward travel of the endless chain to the inward travel.

The apparatus comprises, among other things, a device operated to carry a series of trays along beside a stationary table by an endless chain. The trays are adapted, with suitable mechanism, to contain articles to be packed and always to remain with one side up while traveling around with an endless chain.

Referring to the drawings in detail, *a* is a motor adapted to drive the sprocket wheels *c* suitably mounted through the gear connections, clearly shown in Figs. 2 and 4. The wheels *c*, together with sprocket-wheels *d*, carry endless chains *e*, (one on each side of the apparatus) which are adapted to operate any desired number of trays. The trays *a¹*, *b¹*, *c¹*, etc., are provided with front and rear rollers, as shown, which are supported on the tracks *g*, best seen in Fig. 3. The front rollers have their axles extended to cooperate with the bearings *q* carried by the chain (see Fig. 5). These front rollers to this extent differ from the rear rollers of each tray, so that, as can be seen from the drawing, the rear rollers, when they leave the track *g* (Fig. 2) can be carried, together with the rear end of the tray, between the two endless chains shown, and passed onto the lower track *g* (the tracks being mounted suitably, as shown in the frame) by mechanism now to be described.

On the shaft *r* is a sprocket-wheel (see Fig. 5) which, together with a wheel mounted on the shaft *m* in the frame, carries a chain. This chain transmits motion from the driving shaft to the sprocket-wheels loosely mounted on the bearing shaft *m*.

It is to be understood, as is clear from Fig. 4 of the drawings, that each side of the apparatus is similar and the side opposite that shown in Fig. 5 has the identical arrangement of mechanism as that shown in Fig. 5.

The shaft *m* has mounted fast thereon a pivot-cam which operates on two levers *n* pivot-

ally mounted on opposite sides of the arm *o* which is loosely mounted on the shaft *m* and fast to the sprocket thereon. The inner ends of these levers are spring-pressed against 5 the cam and the outer ends are hook-shaped to coöperate with the slots *l* in each end of the arm *o* to grip the extending pins *k* of the rollers at the rear of each tray, and thus hold the rear of each tray as it leaves the 10 upper track *g* until that end of the tray has been placed on the lower track *g* in a way to be later described.

The mechanism by which the trays are transferred from the lower track to the upper one is shown best in Fig. 2 and differs 15 in certain respects from the mechanism just described. The shaft *p* is mounted in the frame outside the space inclosed by the chain *e*. A chain-gear connection, as shown, 20 transmits motion from the wheel *d* to the shaft *p*. It will be noticed that the front ends of the trays on their outward passage are the rear ends on their rearward passage, and vice versa. The shaft *p* has 25 mounted thereon an arm *s* similar to the arm *o* on the shaft *m* but differing therefrom in that there are no levers *n*, *n* mounted thereon. A semi-circular track *h* coöperates with the arm *s* to pass the ends of the trays from 30 the lower to the upper track. The arm *s*, as shown, has slots provided in its ends to coöperate with the pins of the rollers not fastened to the chain *e*.

The operation of the apparatus, so far 35 described, is as follows: The tray *c*¹ is pulled along the upper track by the endless chains. When the forward end of the tray reaches the circumference of the wheel *c* and is about to pass from the outward to the 40 rearward travel of the chains, the slots in the arms *o*, one on each side of the apparatus, engage the pins *k* of the rear rollers. The shaft *m* is so geared to the shaft *r* and the trays are so placed along the chains that 45 the engagement of the pins *k* will take place at exactly the right moment. At the same time that the slots *l* coöperate with the pins *k*, the cam, which is designed for the purpose, will force the hooked ends of the pivotally mounted levers *n* around the pins to hold them securely in the slots. The cam is designed so that the hooked ends of the levers will release the pins only after the 50 arm *o* in its rotation has carried the rear end of the tray from the top track *g* to the bottom track *g*.

As can be easily seen from Fig. 5 of the drawings, the apparatus is designed so that the passage of the tray from the top to the 55 bottom track takes place without turning the tray over. The same side of the tray remains the upper side at all times. As may also be seen from the drawing, the rear rollers of the tray are kept on a substantially horizontal line with the front

rollers so that the tray in its passage, not only remains with the same side up but also remains level. The operation of this part of the apparatus may be seen so clearly from the drawings that more detailed description is thought to be unnecessary. 70

When a tray passes from the bottom to the top track, the slots in the arm *s* engage the pins *k* (see Fig. 2) and the rotation of the arm forces the rollers around the track 75 *h* while the rollers fastened to the chain pass around the wheel and keep the tray on a horizontal line. The small track *g*¹ affords a bridge for supporting the rear rollers for the passage from the releasing position of 80 the arm *s* to the track *g*.

From the operation described and from the drawings it can be seen that the trays pass around the cycle of operations with the same side always up and always level. 85 It may be also seen that the arms *n* and *s* are continually operating with the trays. As the arms finish with one tray by releasing it from one end for its passage along the track the opposite ends engage the next 90 succeeding tray to aid in its transfer from track to track. All the available space for the trays carried by the endless chains, which it is possible to use, is used.

The apparatus is used for packing as follows: The packers sit on each side of the table *i* (Fig. 1). The trays, in their travel, pass along between the packers, each tray having a certain kind and number of pieces of candy, or other article to be packed,— 100 the kinds in each tray usually differing from the other trays. The number of pieces in each tray is determined by the number of packers working. These pieces, in proper number, are placed on each tray by 105 an operator sitting at the end *A*. As each tray passes a packer, that packer must take the proper number of pieces therefrom and as the tray is traveling at a uniform speed past each packer, the speed of packing is 110 regulated. If any packer neglects to take the proper share from each tray then the tray will return to the operator at the end *A* still containing one or more of the articles to be packed. A check is thus obtained on 115 the work of the packers which immediately gives notice when the packing is not progressing as desired. Where notice is given as soon as trouble arises, the trouble can be easily located and the mixture of the 120 goods packed be kept uniform.

The results obtained from the apparatus described are, increased attention to the work on the part of the packers, and a means of insuring the uniformity of packages, such as mixed chocolates and the like. 125

The apparatus may be used for any purpose where it is desired to pass containers around with an endless belt while keeping them uniformly level and right side up. 130

What we claim, is:—

1. A packing table comprising a frame, tracks mounted thereon at different levels, endless chains mounted in said frame, driving means therefor, trays, one end of each tray being fastened to said chains and the other end of each tray being supported on said tracks, rotating arms mounted in said frame, gear connections between said arms and said driving means, said arms being arranged to support the free ends of said trays when they leave the tracks at one level and carry them to the tracks at another level while the other ends of the trays pass from one set of tracks to the other by means of the chains, said arms making a half revolution while said chains change from the outward to the inward path of their cycle of operations, all arranged so that the trays remain level at all times.

2. A packing table comprising one upper and one lower set of tracks, the lower set terminating at one end in a semi-circular track, an endless chain, and sprocket-wheels mounted in the frame, the greater part of said chain arranged in close proximity to said tracks, trays with rollers adapted to ride on said tracks, one end of each tray being fastened to the chain and the other end being freely rotatable, arms

mounted on the frame with gear connections to the sprocket-wheels, the trays and arms so arranged that at each half revolution of the arms they will engage the free end of one tray and transfer it from one set of tracks to the other, mechanism connected with some of the arms to coöperate in the transfer of the trays, the other arms coöperating with the semi-circular portion of the lower tracks, all for the purpose described, and a table portion mounted on said frame in close proximity to which the trays are adapted to pass.

3. A packing table comprising a frame, an endless conveyer mounted therein, driving means therefor, trays, one end of each tray fastened to said conveyer and the other end of each tray free from the conveyer and supported by the frame, rotatable members arranged to support the free end of a tray and transfer said free end from one level of the frame to another level while the conveyer transfers the other end of same tray between the two levels of the frame.
